APPARATUS FOR USE IN FACSIMILE TRANSMITTING SYSTEMS

Otho Fulton, New York, N. Y.

Application January 9, 1938, Serial No. 58,281

4 Claims. (Cl. 178—11)

This invention relates to facsimile systems (commonly called picture transmission systems and hereinafter referred to as such) and more particularly to a mechanism that may be used at the transmitter or receiver of such systems.

5 A typical facsimile transmitting system is described in Patent No. 1,759,303, dated May 20th, 1930, or in the pending application Serial No. 33,039, filed July 25th, 1935.

10 More specifically, the present invention relates to mechanism which may be used at the transmitter or receiver in the systems described in the aforesaid patent and application, or with other systems wherein the transmitter and receiver are 15 operated in synchronism.

For the sake of brevity in the specification and claims, the material (a film, sheet of paper, foil or the like) to be scanned at the transmitter, and the material on which the reproduction is made 20 at the receiver are termed a "sheet."

The element for scanning the sheet at the transmitter (a light sensitive tube, a stylus or the like) and the element for recording at the receiver (a lamp, stylus' pen, pencil or the like) 25 are hereinafter termed "translating means."

The circuit including the translating means at the receiver and transmitter is hereinafter termed the "picture circuit"; and the circuit for controlling the operation of the transmitter and receiver is hereinafter termed the "operating circuit," or "control circuit."

It is customary to employ a transmitter having a rotary drum carrying the sheet. Hereinafter, for the sake of brevity, the matter to be transmitted from the sheet is termed a "picture", it being understood that this may be on a photographic negative or positive, or any other similar transparency, through which a light beam is projected, the emergent beam being received on a 35 light sensitive cell or the like. The picture may be on opaque paper where it is scanned by reflected light. In some systems, a metal foil on which the picture is printed with insulating ink is used, so that the picture circuit is interrupted 40 when a translating stylus passes over the ink.

45 At the receiver is a drum similar to that at the transmitter, means being employed to rotate the transmitting and receiving drums in synchronism. On this drum is wrapped the sheet on which the 50 picture is to be received. This sheet may be a photographic film, which is acted upon by a suitable source of light, or it may be a paper adapted to be marked upon by a pen or pencil, or the paper may be treated so that it will react electrolytically 55 to a conducting stylus contacting therewith, the

latter method being employed when a metal sheet with insulating ink is used at the transmitter.

One of the objections to any of the systems of the foregoing general description is that the pictures are necessarily limited to the size of the drums employed and the sheets must be put on the drum, each time the transmitting drum has been scanned, or when the complete picture has been received on the receiving drum.

One of the objects of the present invention 10 is to eliminate this difficulty by arranging the sheets at the transmitter and receiver so they can be taken from a continuous delivery roll and this enables pictures of any length to be made without the necessity of using separate sheets, or 15 stopping the transmitting and receiving mechanisms regardless of the length of any individual or series of pictures or documents being transmitted.

Still another object of the invention is to increase the speed at which picture transmission 20 systems may be operated, for the time lost in changing sheets with the existing systems is eliminated by this invention; and because the operation is continuous, the apparatus may be 25 operated at higher speeds than known systems; and if a roll of paper or film sufficiently large is put on the machine, it may be continuously operated throughout the day or night without attention, means being provided, if necessary, to stop 30 and start the transmitters and receivers automatically.

Another object of the invention is to provide a picture transmission apparatus in which a translating means such as a light sensitive cell at the 35 transmitter or a recording lamp at the receiver, either included in the picture circuit, is movable relative to the sheet being scanned or on which the picture is recorded.

A further object is to provide apparatus embodying a motor, a translating device of the picture circuit rotatably driven by said motor and means for moving a sheet relative to said translating device, said means being operated by said 40 motor.

45 Other objects of the invention will be apparent from the following specification, the invention consisting substantially in the construction, combination, location and relative arrangement of parts, all as will be more fully hereinafter set 50 forth and as shown by the accompanying drawing and finally pointed out in the appended claims.

55 For the sake of illustration, the invention will now be described as applied to a two wire circuit

connecting two instruments, over which wires is transmitted the operating current for synchronizing the transmitter and receiver and the picture current for causing the picture to be reproduced at the receiver. Obviously, one wire and ground may be used, or a radio link, by means well understood by those skilled in the art. The present invention does not depend on the type of circuit or channel used to connect 10 the instruments.

Referring to the drawing:

Figure 1 is a diagram illustrating the general assembly of the apparatus;

Figure 2 is a detail view of a portion of the 15 apparatus, Figure 1, illustrating the arrangement of the translating element at a transmitter, said element comprising a light sensitive cell;

Figure 3 is a detail view of a portion of the 20 apparatus, Figure 1, illustrating the arrangement of a translating element at a receiver, said element comprising an electrolytic stylus;

Figure 4 is a view, partly in section, on the line 4—4, Figure 1;

Figure 5 illustrates an alternate form of construction of the carrier or ring supporting the translating elements; and

Figure 6 is a diagram illustrating the operation of the carrier shown in Figure 5.

The numeral 10 denotes a platen arcuate in 30 cross section as shown in Figure 2 which, in the case of a transmitter, may be made of glass or other transparent material, as indicated at 10a in Figure 2, if the instrument is to translate or scan from photographic film by means of light. 35 The receiver will also have a platen of glass similar to the transmitter if the recording is to be done on a photographic film and a suitable light source is substituted for the light sensitive cell 42a, Figure 2, a suitable lens being interposed 40 between the light source and the upper surface of the film on which the picture is to be recorded.

When the apparatus is used for receiving pictures electrolytically, then the arrangement 45 shown for the sake of illustration in Figures 1 and 3 is employed where the platen 10 is made from suitable conductive material, or of bakelite having an upper conducting surface.

Positioned above the platen are clamps 11, 12, 50 having shafts supported in bushings 13, 14 which are in turn supported in the side plates 15, 16, which plates are mounted on the base 17 of the instrument. Springs 18, 19 tend to hold the clamps downward and the clamps are connected 55 by a cross member 20 which enables them to be pulled upward so that a sheet 21 may be drawn beneath them. The bottom surface of the clamps are arcuate and when the clamps are in position on the platen, the sheet is held firmly against 60 the upper arcuate surface thereof.

The sheet is taken off a delivery roll 22, mounted on base 17, passes over a moistener roller 23 (in the case of a receiver using electrolytic paper) an upper roller 24 being employed, if necessary, and these two rollers are geared or otherwise connected so they operate together to moisten the sheet without leaving any excess liquid thereon.

70 The moistener rollers 23, 24 may be used to apply a sensitizer or developer or any other fluid to the sheet 21 in the event this sheet requires the application of such a fluid. The rolls may be arranged on the left hand side of the platen, so 75 as to make application of the fluid after the

translating means 42 has operated on the sheet 21.

Assuming the sheet to have passed the rolls 23, 24, it then passes over the platen 10, against which it is held by the clamps as just described. 5 It then passes beneath the operating rollers 25, 26 supported on the base, the upper one of which may merely act as a weight although these rollers may be connected to roll together and may be spring-pressed to insure their firmly gripping 10 the sheet to move the same. Roller 26 is provided with a ratchet wheel 27 engaged by a stop pawl 28, the arrangement being such that when the wheel 27 is revolved, as hereinafter described, the rollers 25, 26, will grip the sheet and pull it 15 across the platen a definite distance determined by the pitch of the teeth on 27, the stop pawl 28 holding the sheet locked when the wheel 27 is not in motion. This arrangement, together with cams 45, lever 46 and pawl 48 hereinafter 20 described, constitute a step-by-step feeding arrangement for the sheet 21.

By reason of the action of the delivery roll 22 and the drag on the sheet caused by the moistener rolls 23, 24 and because of the presence of the 25 clamps 11, 12, the sheet is held smoothly against the upper arcuate surface of the platen 10 but moves smoothly across the platen in the direction of the arrow 49 when the feeding mechanism is 30 operated.

A rotatable member, such as the carriage or ring 29, is supported in roller bearings 30, 31, 32 journaled in the side plates 15, 16. This ring may be made of any suitable material, such as bakelite, and has teeth, as shown at 33, forming 35 an internal gear thereon, which gear is engaged by a toothed pinion 34 connected to the driven member of a clutch 35, which may be of any suitable type such as that shown in the aforesaid patent or application. The driving member of 40 the clutch is connected to a suitable motor 36.

Insulatedly supported in the ring 29 is the conducting ring 37 which makes continuous contact with a conducting brush 38, to which is connected one side 39 of the picture circuit, the other side of 45 said circuit being connected to the platen 10 via the conductor 40, in the case of an electrolytic receiver.

In the case of an electrolytic transmitter, the arrangement would be the same as for the electrolytic receiver. 50

In case a photographic type receiver is used, the picture circuit would connect to the recording lamp therein in the usual manner. In the case of a photographic transmitter employing a light 55 sensitive cell, the picture circuit would connect to the light sensitive cell 42a in the usual manner.

Extending inwardly from the ring 29 are springs 41 carrying at their inner ends translating elements 42 such as a light sensitive cell, a 60 pen, pencil, lamp, electrolytic stylus or the like. The spring support 41 would obviously be omitted if a cell or lamp is employed, the only function of the spring 41 being to cause the translating element, when necessary, to bear lightly upon the 65 surface of the sheet being scanned or upon the receiving sheet.

If the instrument is to be used as a photographic transmitter, then the element 42 could be a light sensitive cell as shown at 42a in Figure 2, the sheet 21 would take the form of a photographic film 21a, the platen 10a would be transparent, and a suitable lamp 43 would be placed below the platen focused by means of a suitable lens 44 so that the emergent beam would 70 75 80 85 90 95

strike the cell 42a and thereby transmit current over the picture circuit in the usual way. If desired, a suitable lens system can be interposed between the sheet 21a and cell 42a.

5 In connection with an electrolytic transmitting and receiving system, the transmitting arrangement would be different from that described in connection with Figure 2, for in the electrolytic system, the sheet at the transmitter would comprise a sheet of conducting foil or the like having the picture to be transmitted written thereon in insulating ink so as to interrupt the current in the picture circuit in the usual manner.

10 The number of translating elements 42 that are mounted upon the ring 29 will depend upon a number of factors; one or more such elements may be used at the transmitter or receiver depending upon the speed of the apparatus, the 15 number of lines per inch of linear travel of the sheets, and the line across the sheet which is the line scanned at the transmitter or on which the recording is done at the receiver.

15 Assuming that the ring 29 is being revolved in the direction of the arrow 53, Figure 1, and the sheet 21 stretched over the platen 10 is free of any of the elements 42, the cam members 45 engage a lever 46 pivoted at 47 which causes the pawl 48 to engage one of the teeth in the ratchet wheel 27, thereby moving the feed rollers 25, 26 20 which pull the sheet in the direction of the arrow 49 a suitable distance, say one hundredth of an inch if it is desired to make a picture having 100 lines to the inch.

25 By the time this motion of the sheet is completed and the sheet is at rest (the motion of ring 29 having continued) one of the elements 42 passes over the sheet and—depending on the character of this element—makes a line of the picture thereon if the instrument is being used 30 as a receiver, or scans this line if the instrument is a transmitter.

35 Assuming the apparatus is being used as a receiver, and is supplied with a chemically treated sheet and that the element 42 is a stylus, it will be seen that the picture current entering the instrument at 39 passes to the brush 38, to the conducting ring 31, to the spring 41, to the stylus 42, passes through the moistened chemically treated sheet 21, causing the same to change 40 color, flows into the platen 10 and from there, via conductor 40 to the picture circuit, and that this process is repeated as the ring member 29 45 revolves, each successive stylus 42 engaging the paper and translating the incoming current into 50 a visible picture on the sheet, the latter being moved one hundredth of an inch between each 55 engagement of the translating means.

55 Synchronism between the revolving rings 29 at a transmitter and any number of receivers, can 60 be obtained in any suitable manner, such, for example, as by the employment of synchronized motors for the motor indicated at 36, Figure 1, or by the employment of the magnetic clutches or the means disclosed in the patent and pending 65 application hereinbefore mentioned. If the arrangement shown in the patent is used, the locking magnet 50 and its associated armature 51 and lugs 52 to be presently described, may be omitted. The means described in said application, 70 briefly, comprises an ordinary friction clutch for the clutch 35 shown in Figure 1, interposed between the motor 36 and the other moving parts. This rotates the gear 34 continuously and the ring 29 driven thereby, but the ring is stopped at 75 appropriate places by means of the locking mag-

net 50 connected in the control circuit of the system, said magnet operating an armature 51 which engages suitable lugs 52, properly spaced on the ring 29. While the ring 29 is so locked, the clutch 35 slips. This insures that no ring can 5 get out of time with any other ring in the system by more than the error that might occur during the passage of a single translating element 10 42 across the sheet 21 and such errors are constantly corrected and do not become accumulative, as is the case if the rings are continuously rotated by non-synchronous or spring motors.

15 The locking magnets 50 of all receivers, operating from a single transmitter, are, of course, under control of suitable apparatus at the transmitter (such as the contacts 54 to be presently described) and are connected in a control circuit which, in some systems, is the same circuit as that carrying the picture current, or which may be a separate circuit.

20 A pair of contacts 54 may be insulatedly supported on the side plate 16 adjacent the ring 29 so as to affect the control circuit on the distant instrument, and are opened and closed at predetermined points in each revolution of the drum 25 by means of the cams 45 on the ring 29, in order to effect control. Cams 45 may be used to operate the contacts 54.

25 Figure 5 illustrates an alternate form of construction of the carrier ring whereby a group of 30 translating elements are mounted thereon abreast so that at each passage of each group over the sheet, a plurality of lines are simultaneously scanned or recorded. Here the ring 29a may carry one or more groups of translating elements 35 abreast—for example four electrolytic pens or stylus, 42a, 42b, 42c, 42d. These simultaneously sweep over the sheet 21, and are each connected via the separately insulated rings 37a, 37b, 37c, 37d, with separate picture circuits via contact 40 brushes 38a, 38b, 38c, 38d. A single picture circuit can be employed with suitable synchronous switch mechanism at the transmitter and receiver, several of which are known in the art; or suitable filters can be employed in circuit with 45 each stylus (or scanning means if the apparatus is used at a transmitter).

50 It will be understood that when the arrangement shown in Figure 5 is used at a transmitter, that the same number and arrangement of translating devices are used at the associated receiver, which may have the recording pens or stylus 42a, 42b, 42c, 42d.

55 This arrangement permits of scanning as many lines simultaneously, as there are scanning means 55 mounted abreast at the transmitter, and recording these lines simultaneously at the receiver.

60 This will be further understood by reference to Figure 6 which illustrates either scanning or recording with a group of translating elements or 60 stylus, as shown in Figure 5.

65 In Figure 6 the long lines 42a, 42b, 42c, 42d may represent the path of the first sweep (indicated by arrow 55) of the group of stylus over a sheet. The sheet then moves in the direction of the arrow 56 and all the stylus simultaneously take the tracks as shown by short lines of the 57 series—42a to the adjacent line 51a—42b to 51b—42c to 51c—42d to 51d. The sheet then moves another line and the stylus now move from 70 the 57 series of tracks to the adjacent 58 series and then to the 59 series.

75 At this point, if the sheet merely moved one line, stylus 42a would retrack over line 42b which cannot be permitted. So, when this position is 75

reached, the sheet feed mechanism is so arranged that when stylus 42a leaves track 58a the paper is moved and stylus 42a will on the next sweep track at line 60, 42b at 61, 42c at 62 and 42d at 63, and the operation just described is repeated. Thus by feeding the sheet a line at a time until the first stylus (42a) begins to run into the tracking of an adjacent stylus (42b) and then jumping the sheet a sufficient distance (always greater than one line and depending upon the number of stylus used) to give the first stylus room to track, overtracking is prevented. To accomplish this, it is only necessary to make simple changes in the cams 45 and associated mechanism of the step-by-step feed which changes are readily perceived by one skilled in the art.

The picture circuit and the control circuits which may be used with the apparatus herein disclosed, vary so widely in their nature and operation that it is not deemed necessary to show an illustrative circuit here, as it will be obvious to those skilled in the art how this apparatus may be employed either at the transmitter or receiver with any of these circuits and systems.

Although the invention has been disclosed in connection with the specific details of preferred embodiments thereof, it must be understood that such details are not intended to be limitative of the invention except in so far as set forth in the accompanying claims.

What is claimed is:

1. In facsimile scanning apparatus, an arcuate platen, a sheet thereon, spring pressed clamps for holding said sheet upon the convex surface

of said platen at a plurality of points thereon, means common to all said clamps to raise same to release said sheet, a member movable over the sheet, and translating means carried by said member and adapted to contact said sheet.

2. In facsimile scanning apparatus, an arcuate platen, a sheet thereon, spring pressed means for holding said sheet upon the convex surface of said platen at a plurality of points thereon, means common to all said clamps to raise same to release said sheet, means for moving said sheet across said platen step-by-step, a member movable over the sheet, and translating means carried by said member and adapted to cooperate with said sheet when same is stationary on said platen.

3. In facsimile scanning apparatus, a convex stationary platen, a sheet supported on the convex face of said platen, means comprising resiliently mounted arcuate clamps engaging said sheet and extending transversely across the same adjacent to the ends of said platen, and means common to said clamps for disengaging them from said paper.

4. In facsimile scanning apparatus, a convex stationary platen, a sheet supported on the convex face of said platen, a pair of arcuate clamping members extending transversely across said sheet for holding the latter in intimate contact with said platen, a translating device and means for moving the same in a path between said clamping members, and means common to said clamping members for raising them to a position spaced apart from said platen.

OTHO FULTON.

35

DISCLAIMER

2,127,331.—*Otho Fulton*, New York, N. Y. APPARATUS FOR USE IN FACSIMILE TRANSMITTING SYSTEMS. Patent dated August 16, 1938. Disclaimer filed March 30, 1939, by *Mae Fenster*, administratrix of the estate of *Otho Fulton*, deceased.

Hereby enters this disclaimer to claims 1 and 2, except where the convex surface of the sheet is held for scanning and except where the translating means carried by the movable member contacts the sheet on its convexly held surface and in which the plurality of clamps are pressed by spring means against the sheet; and hereby enters this disclaimer to claims 3 and 4, except where the convex surface of the sheet is held for scanning and in which the plurality of clamps are pressed by spring means against the sheet.

[Official Gazette April 18, 1939.]
